KARL BARTH, OF ESSEN, GERMANY, ASSIGNOR TO FRIED. KRUPP AKTIENGESELLSCHAFT, OF ESSEN-ON-THE-RUHR, GERMANY.

SELF-DISCHARGING CAR.

1,421,378.

Specification of Letters Patent. Patented July 4, 1922.

Application filed January 14, 1921. Serial No. 437,325.

To all whom it may concern:

Be it known that I, KARL BARTH, residing at Essen, Germany, a citizen of the German Republic, have invented a certain new and 5 useful Improvement in Self-Discharging Cars, for which I have filed an application in Germany April 14, 1919, of which the following is a specification.

This invention relates to a self-discharging car having a bottom adapted to swing toward either side about one of two laterally disposed axes, it being a special object of the invention to simplify the construction of cars of this type.

10 The invention will be further described with reference to the accompanying drawing which shows one embodiment of the subject matter of the invention by way of example and in which:

20 Fig. 1 is a diagram disclosing in cross section the car when ready for loading,

Fig. 2 is a part sectional view of the car after effecting a discharge toward the left, and

25 Fig. 3 is a part sectional view of the car after effecting a discharge toward the right.

Referring to these drawings, the two end walls A¹ of the car are rigidly fixed in parallel to each other on the underframe A 30 thereof. In addition, there are arranged on the said underframe A both at the front and the rear end of the car two sockets A² disposed symmetrically with respect to the middle longitudinal plane of the car. Said 35 sockets serve to lodge two shafts B which extend over the entire length of the car and are operated if desired from the ends of the latter by means of levers G, which may be fixed to the end walls A¹ of the car in one

40 position by means of key bolts H. To each of the shafts B there are rigidly connected crank arms b¹ which are articulated to the bottom C of the car by means of links D. To the underframe A there are further-

45 more provided abutments a³ projecting into the path of the crank arms b¹ and which, when the crank arms come to bear up against them (Fig. 1), allow the said crank arms to execute a rotation only in the in-

50 ward direction. Stops c¹ are provided for the links D at the bottom C of the car, which in their turn, when the said links bear up against them, likewise only permit these links to carry out an inward rotation.

55 On the bottom C there are firmly arranged

supporting surfaces c² destined, on the discharging motion of the bottom C, to settle down on the abutments a³ and thus to limit said discharging motion.

Each of the two side walls E of the car 60 is provided, in the known manner, at its lower edge with bearings e¹, open at the bottom which, when the car is ready for charging, engage journals c³ arranged on the bottom C. With its upper edge each of the 65 side walls reposes in open bearings a⁴ of the end walls A¹ (Figs. 2 and 3). The side walls E are guided in their movements by means of links F lodged on the end walls A¹.

When the car is ready for loading the de- 70 scribed parts assume the position relatively to each other disclosed in Fig. 1. The crank arms b¹ and the links D then are disposed parallel to the middle longitudinal plane of the car and their longitudinal directions coincide so that the weight of the movable parts of the car and the weight of the load will exert no rotary moment on the shafts B. Any accidental inward displacement of the crank arms b¹ in the direction denoted 75 by the arrows x (Fig. 1) is prevented by the key bolts H on the levers G, whereas a movement in the outward direction of the said crank arms is rendered impossible by the abutments a³. As a result of the two 80 shafts B, and therewith of the crank arms b¹ mounted thereon, being fixed in the afore- 85 said manner, the bottom C is likewise firmly secured in its position. For in this case the bottom could only possibly carry out a 90 movement if on the one side of the middle longitudinal plane the links D were enabled to rotate outward relatively to the bottom, such a movement of the links D being, however, prevented by the stops c¹. 95

When the car is to be discharged toward one particular side, say, for instance, toward the left, then, the key bolt H on the left side having been released, the shaft B disposed to the left of the longitudinal plane of the 100 car is rotated in the direction denoted by the appropriate arrow x (Fig. 1). As soon as the crank arms b¹ fixed to the shaft B have been rotated for a certain small distance, the left-hand system comprising the 105 cranks b¹ and the links D collapse under the weight of the load and the bottom C attains the discharge position (Fig. 2) by carrying out a rotation within the link connections existing between the cranks b¹, disposed to 110

the right of the middle longitudinal plane of the car and the respective links D which are fixed relatively to the bottom by the stops a^1 . As the bottom C begins to rotate, the 5 journals c^2 thereof, which are located to the left of the middle longitudinal plane of the car, disengage from the bearings e^1 of the left-hand side wall E. In the course of the 10 subsequent discharge motion, this side wall E then remains suspended in the known manner in the bearings a^4 , whereas the right-hand side wall E is raised. Upon the termination of the discharge motion, the left-hand supporting surfaces c^2 of the bottom 15 bear against the abutments a^3 of the underframe A and thus secure the bottom C relatively to the underframe.

The manner of returning the car into the state ready for loading after the discharging operation has been effected, as also the 20 method of discharging the car toward the opposite side (Fig. 3) will require no further explanation after the foregoing description.

25 I claim:

1. A self discharging receptacle comprising a rotatably disposed bottom, a frame structure, said bottom articulated to said frame structure by means of link devices, 30 the elements of which devices when said re-

ceptacle is in loaded position are substantially parallel each to each to form a substantially linear support for said bottom, and abutments for said link devices permitting a collapsing action of said link devices 35 only toward the longitudinal center line of said receptacle.

2. A self discharging receptacle comprising a rotatably disposed bottom, a frame structure, said bottom articulated to said frame structure by means of link devices, the elements of which devices when said receptacle is in loaded position are substantially parallel each to each to form a substantially linear support for said bottom, 40 and abutments for said link devices permitting a collapsing action of said link devices only toward the longitudinal center line of said receptacle, said frame structure having abutments co-operating with said bottom, 45 when said bottom is rotated on the collapse of one of said link devices.

The foregoing specification signed at Essen, Germany, this 15th day of November, 1920.

KARL BARTH.

In presence of—

HANS GOTTSMANN,
JOHANN DECKERS.
